UNITED STATES PATENT OFFICE

160,871

SWIMMING POOL

Kenneth H. Larkin, Kansas City, Mo.

Application October 22, 1949, Serial No. 5,655

Term of patent 14 years

(Cl. D4—4)

To all whom it may concern:

Be it known that I, Kenneth H. Larkin, a citizen of the United States, residing at Kansas City, in the county of Jackson and State of Missouri, have invented a new, original, and ornamental Design for a Swimming Pool, of which the following is a specification, reference being had to the accompanying drawings, forming part thereof, in which

Fig. 1 is a plan view of a swimming pool embodying my new design,

Fig. 2 is a sectional view of the swimming pool taken along the line 2—2 in Fig. 1 in the direction of the arrows.

Fig. 3 is a perspective view of the swimming pool.

I claim:

The ornamental design for a swimming pool, substantially as shown.

KENNETH H. LARKIN.
